UNCOUPLING MECHANISM

Martin P. Blomberg, Hinsdale, Ill., assignor to
 General Motors Corporation, Detroit, Mich., a
 corporation of Delaware

Application July 24, 1944, Serial No. 546,366

10 Claims. (Cl. 213—170)

This invention relates to uncoupling mechanism of the type used in connection with railway vehicles to make it possible to unlock the coupler from either side of the vehicle by manipulating a handle located at each side.

It is an object of the invention to provide such mechanism which may be easily and quickly connected to standard couplers, particularly to those of the rotary lock type, and which after being so connected, is positively retained against detachment therefrom. This is accomplished by forming the adapter, which is the part which engages the rotary lock lifter, in two pieces which after they have been assembled in position in openings in the coupler, overlap each other and are then riveted or bolted together so that they thereafter function as though the adapter had been made in one piece.

A further object is to provide an uncoupling mechanism which will be extremely simple in construction, and which may easily and quickly be mounted in position upon any type of railway vehicle equipped with a coupler of the type the adapter is intended for use with.

Other objects and advantages of the invention will be apparent upon reference to the specification and accompanying drawings, in which

Fig. 1 is an end elevation of a railway vehicle, showing my improved uncoupling mechanism associated therewith.

Fig. 2 is a plan view of the structure shown in Fig. 1.

Fig. 3 is a side elevational view of the structure shown in Figs. 1 and 2.

Fig. 4 is an enlarged side elevational view of a portion of the structure shown in Fig. 3, with parts broken away.

Fig. 5 is an enlarged perspective view showing the details of construction of the adapter.

Fig. 6 is a sectional view taken on the line 6—8 of Fig. 5.

The reference numeral 10 indicates a coupler head and 12 is the shank thereof which is supported in the coupler pocket 14, the latter being secured to the car under frame 16. 18 is a lifter which normally is in the downward position shown in Fig. 3, and which, when rotated upwardly by mechanism to be presently described, serves to unlock the coupler to permit adjacent cars to be uncoupled. The above described structure is shown in dot-and-dash lines since it is of conventional construction and forms no part of the present invention.

20 is an adapter which straddles the coupler and is pivotally supported in openings 22 provided in

each side thereof. For purposes of installation in the coupler, this adapter is formed of two generally L-shaped members 24 and 26, which after assembly are secured together, as best shown in

5 Figs. 5 and 6. Referring particularly to Fig. 5, the member 24 is comprised of a horizontally extending portion 28 which is of semi-cylindrical shape in cross-section, there being a longitudinally extending groove 30 formed in its flat face. 10 Extending upwardly from one end of the portion 28 is an arm 32 which has a rectangular shaped boss 34 formed at the point where it connects with the portion 28, there being a hole 36 extending through this boss. A similar boss 38 having a 15 hole 40 extending therethrough is formed at the opposite end of the portion 28. The arm 32 is provided with an angularly extending portion 42 adjacent its upper end, there being an outwardly extending projection 44 formed at the point where the portion 42 merges with the arm 32. The upper end of the portion 42 extends outwardly at a right angle thereto and is of cylindrical shape in cross-section to form a pintle portion 46, which is adapted to fit into one of the openings 25 22 in the coupler to pivotally support the adapter.

The member 26 is similar to the member 24, except that it is opposite hand, its horizontally extending semi-cylindrical portion 48 being provided on its flat face with a tongue 50 which is 30 adapted to fit within the groove 30 on the portion 28 to properly position the parts relative to each other when they are being assembled together. Arm 52 and angularly extending portion 54 of the member 26 have a projection 56 formed at

35 their point of junction, while a pintle portion 58 extends outwardly from the upper end of the portion 54. At the lower end of arm 52 a rectangular shaped boss 60 having a hole extending there through is formed, while at the opposite end of the portion 48 a similar boss 62 having a 40 hole therein is provided.

When the adapter is to be connected to the coupler, the members 24 and 26, which at that time are not secured together, are placed in such 45 position as will permit the pintle portions 46 and 58 to fit into the openings 22 in the coupler. Thereafter the semi-cylindrical portions 28 and 48 are placed together so that their flat faces will bear against each other, with the tongue 50 fitting within the groove 30. Then rivets 64 are 50 passed through the aligned holes in the bosses 34 and 62 and bosses 38 and 60 and are headed over to serve to rigidly connect the members 24 and 26 together so that they will function as though 55 they had been made as a single part. It will be

noted that when the portions 28 and 48 are secured together, the resultant combination is of cylindrical shape in cross-section, as shown in Fig. 6. Bolts or any other suitable securing devices may of course be used instead of the rivets 54 to fasten the two members together.

Referring now to Figs. 3 and 4, 66 is a link having an elongated slot 68 formed in one end, and an inverted U-shaped portion 70 at the other end. This U-shaped portion is adapted to fit over the cylindrical section formed by the two portions 28 and 48 after they have been secured together. A bolt 72 having a nut 74 threaded thereon is inserted through a hole formed in leg 73 of the U-shaped portion and serves to hold the latter in place on the cylindrical central part of the adapter. Extending through the slot 68 is the central portion 76 of a bail formed of bar stock, which is bent rearwardly to form portions 78 and 80, which have connected to them upwardly extending portions 82 and 84, the ends of which are bent around to form eyes 86 and 88. The purpose of the slot 68 in the end of the link is to permit the latter to swing to angular positions relative to the central portion 76 of the bail when the coupler swings sidewise when the car is rounding curves, and also to allow for movement of the coupler toward the car when the draft gear is compressed during buffing action between two cars.

90 is an uncoupling rod which is journalled adjacent its inner end in a support 92 secured to the coupler pocket by bolts 94, and at its outer end in a support 96 which is secured by bolts 98 to a bracket 100 which extends downwardly from the car underframe. The outer end of this rod is bent downwardly at 102 and then inwardly and forwardly as at 104 to form a handle portion which is accessible from the side of the car. The inner end of the rod 90 extends through the eye 86 of the bail and is bent around in U-shape as at 106 to form an outwardly directed projection 108. The U-shaped portion 106 bears against a stop 110 which is welded to the coupler pocket, this serving to limit axial movement of the uncoupling rod 90 in its supports 92 and 96.

At the other side of the coupler, uncoupling rod 112 is bent downwardly to form portion 114 which then is bent in U-shape as at 116 to provide an outwardly directed projection 118 which extends through a support 120 which is secured by bolts 122 to the coupler pocket and which serves as the inner pivotal support for the uncoupling rod. The outer end of the latter is not shown but is similar in construction to the other side, there being a handle portion provided on the rod which is accessible from that side of the car. The U-shaped portion 116 bears against a stop 124 which is welded to the coupler pocket and serves to limit axial movement of the rod 112 in its pivotal supports.

Secured to the upwardly extending portion 82 of the bail is a lug 126 which has connected to it one end of a tension spring 128, the opposite end of which is connected to a bracket 130 secured to the underside of the coupler pocket. The purpose of this spring is to normally hold the bail and the parts connected to it in the position shown in the full lines in Figs. 2 and 3.

When it is desired to unlock the coupler from the left hand side of the car, as viewed in Figs. 1 to 3, the handle 102 is swung upwardly in a counter-clockwise direction. This of course rotates the rod 90 in its supports 92 and 96, causing the projection 108 to engage the upwardly

extending portion 82 of the bail, thereby swinging the bail away from the car, or to the right as viewed in Fig. 3. Since the link 66 connects the bail to the adapter 20, the latter is likewise swung in the same direction about the pivot point where the pintle portions 46 and 58 fit into the openings 22 in the opposite sides of the coupler, thereby causing the projections 44 and 56 to engage the lifter 18 and to rotate the latter upwardly which unlocks the knuckle of the coupler so that adjacent cars may be uncoupled. This position of the uncoupling rods, the link and the adapter are shown in dot-and-dash lines in Figs. 2 and 3.

After the uncoupling operation has been completed and the handle 102 has been released by the operator, the spring 128 serves to return the parts to their normal position, indicated in full lines in Figs. 2 and 3. When the uncoupling mechanism is in this position, the knuckle of the coupler is in position wherein it will interlock with the knuckle of an adjacent car when the two cars are to be coupled together, and will be locked in that position until the uncoupling mechanism is operated to unlock it. It will be understood that the knuckle of each coupler locks independently of the other, and that adjacent cars are held together by this interlocking action of the knuckles on the two couplers.

It will be noted that when the coupler is being unlocked by rotation of the uncoupling rod 90, the uncoupling rod 112 on the other side of the car is not disturbed, since the upwardly extending portion 84 of the bail merely swings away from the portion 114 of the rod 112, forming what is in effect a lost motion connection between the uncoupling rod and the bail. The purpose of having the eyes 86 and 88 encircle the rod 90 and the projection 118 respectively is to support the bail from and connect it to the uncoupling rods in such manner as to provide this lost motion connection.

When it is desired to unlock the coupler from the right-hand side of the car, as viewed in Figs. 1 to 3, the handle portion at the outer end of the uncoupling rod 112 is swung away from the car, thereby rotating that rod and causing the portion 114 thereof to engage the upwardly extending portion 84 of the bail, which swings the latter away from the car, and as previously described, through the connection of the link 66 rotates the adapter 20 which raises the lifter 18 thereby unlocking the coupler. During this movement, the portion 82 on the opposite side of the bail merely swings away from the projection 108 so that the rod 90 is not caused to move. When the handle on the uncoupling rod 112 is released, the spring 128 serves to return the parts to their normal position, as previously described.

While a specific embodiment of my uncoupling mechanism has been illustrated and described, it will be understood that various changes in size, shape and arrangement of the parts may be made without departing from the spirit and scope of the appended claims.

I claim:

1. In an uncoupling mechanism for car couplers equipped with a lift lever for unlocking the coupler, a two-piece member pivotally supported on said coupler and adapted to engage said lever, a bail, a link connecting said member to said bail, and an uncoupling rod extending to the side of the car, said rod when rotated being adapted to engage said bail to move the latter whereby the

member will lift said lever serving to unlock the coupler.

2. In an uncoupling mechanism for car couplers provided with a rotary lock lift lever, a two-piece adapter pivotally supported on said coupler and adapted to engage said lever, a bail, a link connecting said adapter to said bail, and an uncoupling rod connected to said bail and extending to the side of the car, said rod when rotated being adapted to engage said bail to move 10 the latter whereby the adapter will lift said lever serving to unlock the coupler.

3. In an uncoupling mechanism for car couplers equipped with a lift lever for unlocking the coupler, a two-piece member pivotally supported 15 in openings on opposite sides of the coupler and adapted to engage said lever, a bail, a link connecting said member to said bail, and an uncoupling rod connected to said bail and extending to the side of the car, said rod when rotated being adapted to move said bail whereby the member will lift said lever serving to unlock the coupler.

4. In an uncoupling mechanism for car couplers equipped with a lift lever for unlocking the coupler, an adapter pivotally supported in 25 openings on opposite sides of the coupler and adapted to engage said lever, said adapter comprising two overlapping members which are separately inserted in said openings and are thereafter secured together to form the complete adapter, a bail, a link connecting said adapter to said bail, and an uncoupling rod extending to the side of the car, said rod when rotated being adapted to engage said bail to move the latter 30 whereby the adapter will lift said lever serving to unlock the coupler.

5. In an uncoupling mechanism for car couplers equipped with a lift lever for unlocking the coupler, an adapter pivotally supported in openings on opposite sides of the coupler and adapted 40 to engage said lever, said adapter comprising two generally L-shaped members the lower legs of which are adapted to overlap each other when the upper ends have been separately inserted in said openings and are thereafter secured together to form the complete adapter, a bail, a link connecting said adapter to said bail, and an uncoupling rod extending to the side of the car, said rod when rotated being adapted to engage said bail to move the latter 45 whereby the adapter will lift said lever serving to unlock the coupler.

6. In an uncoupling mechanism for car couplers equipped with a lift lever for unlocking the coupler, an adapter pivotally supported in openings on opposite sides of the coupler and adapted to engage said lever, said adapter comprising two generally L-shaped members the lower legs of which have portions which are of semi-cylindrical shape in cross-section and which are adapted 55 to overlap each other when the upper ends of the members have been inserted in the openings after which the members are secured together to form the complete adapter, the flat inner faces of the two semi-cylindrical portions fitting against each 60

other so that their outer surfaces together form a cylindrical portion, a bail, a link having a U-shaped hook at one end which fits over said cylindrical portion and a slot at the other end, said bail extending through said slot, and an uncoupling rod connected to said bail and extending to the side of the car, said rod when rotated being adapted to move said bail whereby the adapter will lift said lever serving to unlock the coupler.

7. In an uncoupling mechanism for car couplers equipped with a lift lever for unlocking the coupler, a two-piece member pivotally supported on said coupler and adapted to engage said lever, a bail, a link connecting said member to said bail, and an uncoupling rod extending to the side of the car, said rod when rotated being adapted to engage said bail to move the latter whereby said member will lift said lever serving to unlock the coupler, said bail being supported by said uncoupling rod.

8. In an uncoupling mechanism for car couplers equipped with a lift lever for unlocking the coupler, a two-piece member pivotally supported on said coupler and adapted to engage said lever, a bail, a link connecting said member to said bail, and a pair of uncoupling rods extending to opposite sides of the car, said rods when rotated being adapted to engage said bail to move the latter whereby said member will lift said lever serving to unlock the coupler, said bail having eye portions formed at its upper ends, one of said uncoupling rods extending through each of said eye portions whereby the bail will be connected to said said uncoupling rods and will be supported therefrom.

9. In an uncoupling mechanism for car couplers equipped with a lift lever for unlocking the coupler, a U-shaped two-piece member adapted to engage said lever and having pintle portions formed at its upper ends, said pintle portions extending into openings provided in the opposite sides of the coupler to form pivotal supports for said member, a bail, a link connecting said bail with said member, and an uncoupling rod extending to the side of the car, said rod when rotated being adapted to engage said bail to move the latter whereby the member will lift said lever serving to unlock the coupler.

10. In an uncoupling mechanism for car couplers equipped with a lift lever for unlocking the coupler, a U-shaped two-piece member having pintle portions formed at its upper ends and projections extending laterally from the intermediate portions of its vertical legs, said pintle portions fitting into openings provided in the opposite sides of the coupler to form pivotal supports for said member, a bail, a link connecting said bail with said member, and an uncoupling rod extending to the side of the car, said rod when rotated being adapted to engage said bail to move the latter whereby the projections on said member will engage said lever to lift the latter and thereby unlock the coupler.

MARTIN P. BLOMBERG.
